CLAIM

I claim the ornamental design for a wireless card reader, as shown and described.

DESCRIPTION

FIG. 1 is a perspective view of a first embodiment of a wireless card reader, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of a second embodiment of the wireless card reader; and,

FIG. 9 is a top plan view thereof.

The front, rear, right side, left side elevational views and the bottom plan view of the second embodiment of the wireless card reader are the same as those of the first embodiment and, therefore, are not shown.

Broken lines are for illustrating unclaimed portions of the wireless card reader; the broken lines form no part of the claimed design.
